VANITY COMPACT

Brantley Joseph Landry, New Orleans, La.

Application August 23, 1949, Serial No. 111,880

2 Claims. (Cl. 132—83)

1

This invention relates to an improved vanity compact containing a lipstick pencil besides compartments for face powder and rouge, the primary object of the invention being to provide a compact of this kind containing a lipstick pencil which is projectable for use from the case of the compact and retractable into the case when not in use, the compact also containing a mirror which is movable relative to the case to a certain angular position for efficient application of the lipstick pencil, and movable to another position suitable for application of face powder and/or rouge from the corresponding compartments, means being provided to positively hold the mirror in either angular position.

Other important objects and advantageous features of the invention will be apparent from the following description and the accompanying drawings, wherein, merely for purposes of illustration, a specific embodiment of the invention is set forth in detail.

In the drawings:

Figure 1 is a side or edge elevation of the compact in closed position;

Figure 2 is a bottom plan view of the compact;

Figure 3 is a front end elevation thereof;

Figure 4 is a vertical longitudinal section taken on the line 4—4 of Figure 2;

Figure 5 is a transverse vertical section taken on the line 5—5 of Figure 1;

Figure 6 is a plan view of the compact in fully open position, with the lipstick pencil assembly removed;

Figure 7 is a side elevation showing the compact in partly open position, showing the mirror in lipstick-pencil-applying position in dotted lines, and in powder or rouge-applying position in full lines;

Figure 8 is a transverse vertical section taken through Figure 7 on the line 8—8;

Figure 9 is a perspective view of the lipstick pencil assembly;

Figure 10 is a fragmentary transverse vertical section taken on the line 10—10 of Figure 7.

Referring in detail to the drawings, wherein like numerals designate like parts throughout the several views, the numeral 12 generally designates the substantially elliptical case, comprising upper and lower sections 13 and 14, respectively, of semi-elliptical, longitudinal and transverse cross-sections, the sections 13 and 14 being hinged together on a transverse axis at their rear ends, as indicated at 15. The lower section 14 is somewhat deeper than the upper section 13.

The upper section 13 has an inwardly-project-

ing rim flange 16 defining an elliptical opening 17 in which is adapted to nest a mirror 18 having a frame 19 fitting the opening 17, the rearward end of the mirror and its frame being curvedly truncated, as indicated at 20, so as to be spaced from the adjacent end of the opening 17, as shown in Figure 6. The forward end of the mirror frame 19 has a curved hook 21 projecting through a slot 22 in the rim flange 16 to act as a hinge for the mirror to swing from closed position flush with the rim flange 16 to either of the positions shown in Figure 7. The lower part of the mirror frame 19 has lateral ears or lugs 23, 23 to frictionally fit in conformably-shaped openings 24, 24 in the rim flange 16 to hold the mirror in closed position. The lower end of the mirror frame 19 has two laterally-spaced lugs 25, 25 to engage portions of the lower case section 14 as hereinafter described, whereby the mirror 18 is held in either of the open positions illustrated in Figure 7. Opposite sides of the forward part of the rim flange 16 have recesses 26, 26 formed by punching out portions of the flange and bending the resultant tabs inwardly to provide receivers for the finger tabs 27, 27 on the face powder and rouge compartment closures hereinafter described.

The lower case section 14 has an inwardly-projecting rim flange 28 widened at its rearward end to provide a base plate 29. A substantially semi-cylindrical lipstick pencil assembly chamber 30 is positioned centrally and longitudinally in the lower section 14 and extends from a point near the forward end thereof to a point in substantial spaced relation to the rearward end of the section 14. The forward end of the section 14 is open in the area of the forward end of the chamber 30, as indicated at 31. The rear end of the chamber 30 is closed by a vertical wall 32 having at its upper end a rearwardly-extending plate 33 secured to the base plate 29, as indicated at 34. The bottom of the chamber 30 is secured to the bottom of the section 14 in any suitable manner, as by soldering, in the case of a metal lower section 14.

From the plate 33 forwardly the upper edges of the sides of the chamber 30 are bent laterally outwardly to provide flanges 35, 35. The spaces in the lower case section 14 at opposite sides of the chamber 30 provide compartments 36, 37 for face powder and rouge, respectively. Semi-elliptical closure plates or flaps 38, 39 fitting the tops of the compartments 36, 37, respectively, have downwardly-curved lugs or tabs 40 intermediate their straight inner edges which em-

brace hinge pins 42 formed in the flanges 35, 35, whereby the flaps are hinged on the chamber 30. The outer edges of the flaps are formed with upturned finger pieces 27 facilitating opening the flaps, and fitting into the recesses 26 in the rim flange 16 of the upper case section 13 when the case is closed.

Forwardly of the hinge connections of the flaps 38 and 39 the flanges 35, 35 are formed with longitudinally-spaced pairs of notches 43, 43 and 44, 44 to selectively seat the prongs or tabs 25, 25 in the free end of the frame 19 of the mirror 18, whereby the mirror is positively held in the differently-angulated positions shown in Figure 7.

The lipstick pencil assembly, generally designated 45, which fits in the chamber 30, comprises, as shown in Figures 4, 8 and 9, a tube 46 having a longitudinal slit 47 in its upper side. The forward end of the slit 47 is closed by a cap ring 48 telescoped on the tube 46. The lipstick pencil 49 is projectable and retractable through the ring 48 and extends in the tube 46 and has secured on its rear end an element which rises through the slit 47 and has a finger piece 50 on its upper end bridging the slit and by means of which the pencil 49 is operated to projected and retracted positions. The rearward end of the tube 46 has telescoped thereon a cap 51 having at its top a rearwardly-projecting portion 52 terminating in a downturned pointed lug 53 arranged to project through a slot 54 in the plate 33 to secure the pencil assembly 45 in place in the chamber 30, with the cap engaging the rearward chamber wall 32, as shown in Figure 4. The assembly 45 engages the chamber 30 frictionally and can be easily pried out of the chamber and replaced when desired.

A curved catch 55 is hinged at 56 on the upper forward part of the upper section 13 and terminates at its free end in a hook 57 arranged to embrace a protrusion 58 on the lower forward part of the lower section 14, as indicated in Figure 1, to keep the sections closed. The catch 55 is wide enough to close the opening 31 in the forward end of the lower section and prevent exposure of the lipstick pencil.

The compact case 12 having been opened after release of the catch 55 by upswinging of the upper section 13 relative to the lower section 14, the mirror 18 is then swung forwardly and its prongs 25, 25 engaged either with the notches 43, 43 or the notches 44, 44. When the mirror prongs are engaged with the notches 43, 43, the mirror is somewhat rearwardly tilted, as indicated in dotted lines in Figure 7, in a position in which accurate and easy application of the lipstick pencil 49 is assured. Thereupon, the pencil 49 is pulled out to operative position by means of the finger piece 50 and restored to retracted position by means of the finger piece 50, when desired. With the mirror prongs 25, 25 engaged in the notches 44, 44, the mirror 18 is in a substantially perpendicular position more

suitable to the application of face powder and/or rouge, and in which the flaps 38 and 39 can be opened more widely to provide better access to the powder and rouge compartments 36 and 37.

5 I claim:

1. A vanity compact comprising a case composed of hollow upper and lower sections hinged together at their rearward ends, a longitudinal member in the lower section having sides formed with longitudinally spaced notches, a mirror at the inner side of said upper section and hinged at the forward end of said upper section and having a free end, prongs on the free end of said mirror, said mirror being arranged to be swung forwardly and downwardly when said upper section is in an upwardly swung position relative to said lower section and to selectively engage said prongs with said notches, whereby said upper section is held in a selected open position and said mirror is positively held in a predetermined position of use, said longitudinal member comprising an upwardly-facing channel providing a longitudinal chamber for accommodating a lipstick pencil.

2. A vanity compact comprising a case composed of hollow upper and lower sections hinged together at their rearward ends, a longitudinal member in the lower section having sides formed with longitudinally spaced notches, a mirror at the inner side of said upper section and hinged at the forward end of said upper section and having a free end, prongs on the free end of said mirror, said mirror being arranged to be swung forwardly and downwardly when said upper section is in an upwardly swung position relative to said lower section and to selectively engage said prongs with said notches, whereby said upper section is held in a selected open position and said mirror is positively held in a predetermined position of use, said longitudinal member comprising an upwardly-facing channel providing a longitudinal chamber for accommodating a lipstick pencil, the edges of said channel having laterally-outwardly-projecting flanges in which said notches are formed.
